UNITED STATES PATENT OFFICE.

ADAM E. SCHATZ, OF MOUNT VERNON, NEW YORK.

FURNITURE-CASTER.

1,026,773.

Specification of Letters Patent.

Patented May 21, 1912.

Application filed September 11, 1911. Serial No. 648,633.

To all whom it may concern:

Be it known that I, ADAM E. SCHATZ, a citizen of the United States, residing at Mount Vernon, in the county of Westchester and State of New York, have invented certain new and useful Improvements in Furniture-Casters, of which the following is a specification.

My invention relates to improvements in sliding casters or shoes for chairs and furniture and other utensils and is intended to displace the roller casters heretofore largely used, and is an important improvement on the inventions for which I have heretofore filed applications for Letters Patent, in which a caster is shown having a continuous rounded surface and the legs depending from the periphery. I find in practice, that the sliding caster provided with legs or prongs depending from the periphery must be much smaller in diameter than the chair leg or that section of a piece of furniture to which they are to be applied. In the case of chair legs, there must be an allowance of from an eighth to a quarter of an inch of wood; otherwise the edges of the leg of a chair will be forced or split off, by the leg being forced into the wood, since in many cases the grain of the wood runs in diagonal lines. I find that in many chairs the front or rear legs come forward or backward, and that such curved lines run across the grains. In many cases the front legs at the bottom are tapered, and thus provide but a small surface to attach a sliding caster provided with the prongs in the periphery. The use of the dome shaped casters has proven, that they provide but a small contact surface, which leaves a mark on a hardwood floor, and is soon worn flat, where it is used on marble or tiled floors. When placed under heavy articles of furniture the small bearing points embed themselves in the wood and leave prints and depressed streaks on the flooring, because the bearing surface is too small. In practice I find that these serious objections are all overcome by the use of casters of the form shown in the drawing by reason of the fact that a caster of much greater diameter can be used, and the surface of the curved or raised ring is much greater than can be obtained by the use of the dome shaped caster, since the legs of the casters here shown are stamped from the center of the

material, and thus have much more material to hold to and cannot split the wood.

I do not confine myself to the circular form shown in the drawing, since a triangular or oblong or square shape may be used, without departing from the spirit of my invention, the essential feature of which is providing the legs or prongs in the center of a convexed shoe slide.

In the drawing:—Figure 1 represents a plan view of my invention, showing the prongs or legs which depend from the inner periphery of the shoe. Fig. 2, is a cross-section of the same through the center of Fig. 1. Fig. 3, is a top view of the same, in which the prongs are of a modified form. Fig. 4, is a cross-section of the type of shoe shown in Fig. 3, showing a different form of prong from those shown in Figs. 1 and 2. Fig. 5, is a top or plan view of a shoe in which the inner periphery is provided with small projecting spurs or prongs of a modified form. Fig. 6, is a top or plan view showing another spur or prong, and Fig. 7, illustrates a modified form of caster body provided with a depressed central portion, showing in full lines the portion cut out to form the fastening spurs or prongs.

It will be noted that I have shown the legs in different shapes. In Figs. 1 and 2, the legs *a* are provided with a spear head, and may be provided with a barb on either or both sides, so that when the leg is driven into the wood the spurs will embed themselves in the wood and prevent the caster *c* from dropping off as may be the case, with casters having the form of prongs *b*, as shown in Fig. 3. In Fig. 5, the prongs *d* are spear shaped. In fact any shaped barb having irregular shaped sides may be provided, the object being to provide means by which when embedded in the wood the fibers of the wood displaced or separated by the point will fall back into line as near as possible and clutch the leg more tightly, than it can when it is simply wedged apart as in the V-shaped leg, the tendency in the latter case, being to force the wedge out by reason of changes in the wood by atmospheric conditions, or when the wood gets wet. Sliding chair casters where the legs are V-shaped are now being discarded by many manufacturers and users for the reason that they are apt to drop out of the leg. Another great objection to the use of nickel

steel is that they will rust after being wet. To avoid this, I prefer to construct the casters shown from a non-corrod़ing or non-rusting material having the tensile strength necessary to prevent the contour from being flattened by pressure or hammering. I find that for this purpose aluminum is well suited for my purpose, since it has the hardness and strength of nickel steel, and will polish as well. I find that two prongs are the best form because they can be given greater length than where more legs are employed.

In the drawings, Figs. 2 and 4 illustrate the curvature of the shoe between its inner and its outer periphery.

In the drawings in Figs. 1 and 3, I have shown legs or prongs depending from the inner periphery and in Figs. 5 and 6 different forms of legs. It is to be remembered that in stamping out the disks the legs should be opposite each other at equal distances on the periphery so that when the legs are pressed downward by the dies they will be in a perpendicular position, and are thus more easily driven into the wood, while in Figs. 6 and 7 the legs will depend at an

angle, which, however, does not prevent them from being driven into the wood, and will tend to hold the caster on tightly by reason of each leg depending in an opposite direction, thus tending to securely fasten the caster.

Having described my invention what I claim as new and desire to secure by Letters Patent is:—

1. A metallic sliding caster having an annular raised surface between the inner and outer periphery and provided on the inner periphery with two or more depending legs, constructed of stiff metal, substantially as described.

2. As an article of manufacture, a sliding caster made of non-rusting aluminum and having an annular raised convexed ridge between the periphery and the inner opening, the edges of the inner opening having legs, depending therefrom, substantially as described.

ADAM E. SCHATZ.

In presence of—

E. W. CADY,

ALBERT POPKINS.
